UNITED STATES PATENT OFFICE

158,614

FINGERNAIL GUARD THIMBLE

Joseph J. Quetherera, Trona, Calif.

Application June 15, 1949, Serial No. 3,287

Term of patent 7 years

(Cl. D3—19)

To all whom it may concern:

Be it known that I, Joseph J. Quetherera, a citizen of the United States, residing at Trona, in the county of San Bernardino and State of California, have invented a new, original, and ornamental Design for a Fingernail Guard Thimble, of which the following is a specification, reference being had to the accompanying drawings, forming part thereof.

Figure 1 is a top perspective view of a fingernail guard thimble, showing my new design,

Figure 2 is a bottom plan view thereof, and Figure 3 is a front elevational view of the same.

I claim:

The ornamental design for a fingernail guard thimble, as shown.

JOSEPH J. QUETHERERA.
